UNITED STATES PATENT OFFICE.

KARL HEINEMANN, OF BERLIN, GERMANY, ASSIGNOR TO DEUTSCHE WAFFEN- UND MUNITIONSFABRIKEN, OF BERLIN, GERMANY.

MACHINE-GUN.

1,087,371.

Specification of Letters Patent. Patented Feb. 17, 1914.

Application filed April 7, 1913. Serial No. 758,470.

To all whom it may concern:

Be it known that I, KARL HEINEMANN, a citizen of the German Empire, residing at Berlin, in the Kingdom of Prussia, Germany, have invented a certain new and useful Improvement in Machine-Guns, of which the following is a specification.

The present invention refers to an improvement in machine guns more particularly of the Maxim type, and relates to the trigger mechanism of such guns. And the object of the improvement is to provide a trigger mechanism which can conveniently be actuated by the operator and is less tiring than the trigger mechanism now in use, so that the accuracy in aiming the gun is increased and the same person can for a longer time aim the gun with undiminished accuracy.

With this object in view my invention consists in so arranging the member of the trigger mechanism which is directly acted upon by the gunner, that it is pulled backward by the forefinger or medium finger, instead of being pushed forward by means of the thumb. Thereby the gunner is enabled to firmly grasp the handle provided at the rear of the gun with his palm and the thumb, so that he has a strong hold of the gun. This is particularly of importance for example, when the gun is fired with considerable elevation.

In carrying out my invention there is arranged between the handle of the gun and the vertical double armed rocking lever which is connected with the horizontal trigger bar a horizontal double armed trigger lever the inner end of which is resting against the upper end of the said rocking lever while its outer end is provided with a finger piece forming a rest for the finger actuating the trigger mechanism.

As machine guns are ordinarily equipped with two handles in the preferred form of my invention a trigger lever is provided in front of each of the said handles, and the inner ends of the trigger levers are suitably connected with each other, in order to enable the operator to uniformly and simultaneously act on the trigger mechanism with both hands.

For the purpose of explaining the invention more in detail an example embodying the same has been shown in the accompanying drawings in which the same letters of

reference have been used in all the views to indicate corresponding parts.

In said drawings—Figure 1, is a plan view of the rear part of a gun equipped with my improved trigger mechanism, Fig. 2, is a rear view thereof, Fig. 3, is a side view thereof, and Fig. 4 shows on a smaller scale a lateral elevation, partly in section, of a Maxim gun constructed in accordance with and embodying the invention.

In the drawings only so much of the gun has been shown as is necessary for explaining the invention. The general construction of the gun is known in the art and needs no description.

Referring to the example illustrated in the drawings, on the rear part A of the casing which incloses the breech mechanism a pair of vertical handles *g* and *g'* are provided which are connected with the breech casing by pairs of upper and lower arms *h*, *h'* which are preferably curved. To each of the upper arms *h*, *h'* horizontal brackets *a* and *a'* respectively are secured which are directed inward. The brackets *a* and *a'* are provided with pivot bolts *c* and *c'* respectively for horizontal trigger levers *b* and *b'* respectively.

At their inner ends the trigger levers are preferably cranked, and articulated with each other for example by means of a pivot bolt *e* secured to one of the levers and playing in an elongated hole of the other lever. The free outer ends of the trigger levers are furnished with finger pieces *f* and *f'* which are directed downward and form rests for the finger and are preferably provided with a suitable lining of fiber, leather or the like, whereby they can more conveniently be acted upon particularly in cold weather. The length of the trigger levers is such, that their finger pieces *f* and *f'* are located substantially in front of the handles *g* and *g'* respectively and that their inner ends rest against the rear face of the double armed upright push lever *d* which is pivoted at *i* to the machine frame and actuated by a spring *d'*. The said push lever *d* engages with its lower end a notch in the trigger bar *k* slidable in the longitudinal direction of the gun.

The operation of the trigger mechanism is as follows: The gunner grasps with his hands the handles *g* and *g'* and puts his index fingers against the front sides of the

finger pieces f and f' of the trigger levers b and b' . For firing the gun the gunner pulls one or both finger pieces f and f' with one or both index fingers backward toward the handle or handles g and g' . Thereby the trigger levers b and b' are horizontally rocked in order to swing or rock forward the upper end of the spring actuated push lever d . The lower end of the said push lever being rocked rearward at the same time pulls back the sliding trigger bar k whereby the firing bolt is released in the usual way.

I claim:—

- 15 1. In a machine gun of the type described the combination with the gun frame, of a handle secured thereto, an upright double armed, spring actuated push lever engaging with and operating the sliding trigger bar of the trigger mechanism, of a double armed trigger lever adapted to be pulled backward and to operate the said upright push lever, one arm of said trigger lever being in engagement with the free end of the push lever and the other arm being provided with a finger-piece lying adjacent to the grasping portion of the handle.
- 20 2. In a machine gun of the type described the combination with the gun frame, of a handle secured to the rear of the frame, a trigger mechanism, a slideable trigger bar arranged to operate said trigger mechanism,

an upright double armed, spring actuated push lever engaging with its lower end the said trigger bar, a horizontal double armed trigger lever pivotally fixed at a point intermediate the push lever and the gun handle and adapted to rest with its inner end against the upper end of the push lever, the outer end of the trigger lever being provided with a finger piece substantially in front of the said handle.

3. In a machine gun of the type described the combination with the gun frame, of a pair of handles secured to the rear of the frame, a trigger mechanism, a slideable trigger bar arranged to operate said trigger mechanism, an upright double armed, spring actuated push lever engaging with its lower end said trigger bar, and a pair of horizontal double armed trigger levers, each pivotally fixed at a point intermediate the said push lever and one of the gun handles, the inner ends of the said trigger levers being articulated with each other and adapted to rest against the upper end of the push lever, each of the outer ends of the said trigger levers carrying a finger piece approximately in front of the appertaining gun handle.

KARL HEINEMANN.
